UNITED STATES PATENT OFFICE

2,400,730

NONREFILLABLE CONTAINER

Nicholas Archidiacano, Boston, Mass.

Application July 18, 1944, Serial No. 545,449

1 Claim. (Cl. 215—22)

This invention relates to non-refillable containers and has particular reference to non-refillable bottles and to a novel check-valve unit of simple, inexpensive and efficient construction for incorporation in bottles and other containers to prevent refilling thereof.

The invention has for its object to provide an improved non-refillable bottle or other container, and it also has for its object to provide, as a new article of manufacture, an improved self-contained check-valve unit for incorporation within the outlet of a bottle or other container to render the latter non-refillable.

To these ends I have provided certain improvements relating to bottles or other containers of the class indicated as set forth in the following description, the several novel features of the invention being separately pointed out and defined in the claim at the close of said description.

In the accompanying drawing:

Figure 1 is a central vertical sectional view of a non-refillable bottle constructed in accordance with this invention.

Figure 2 is an enlarged section on line 2—2 of Fig. 1.

Figure 3 is an enlarged section on line 3—3 of Fig. 1.

Figure 4 is a central vertical sectional view of the housing member hereinafter described showing the same in its condition prior to the molding of its upper end portion.

Figure 5 is a top plan view of the housing member shown in Fig. 4.

Figure 6 is a central vertical sectional view of the cage member hereinafter described.

Figure 7 is a top plan view of the cage member shown in Fig. 6.

Figure 8 shows the structure of Fig. 2 in inverted position.

The illustrated embodiment of my invention comprises a bottle 10 made with a tubular neck or spout 11 within which is fixed a flow-controlling check-valve unit that is indicated generally in Figs. 1, 2 and 8 by the reference numeral 12. This unit comprises a one-piece thin sheet metal housing member 13 whose lower portion is made cylindrical so that it can be slid downwardly within the outlet conduit 14 of the neck 11 into position against an annular shoulder 15 formed upon the interior of said neck where it is permanently secured by an annular body 16 of cement.

The lower end of housing member 13 is made with a radial inwardly extending horizontal valve-seat flange 17 (Figs. 2, 3, 4 and 8) which

surrounds a central circular opening or port 18, while the upper end portion of housing member 13 is formed with a vaulted roof or top wall 19 having a centrally disposed circular port 20 at its top. The exterior of the roof portion 19 is made with an annular nipple or spout flange 21 which ensures a smooth flow of the discharging contents of the bottle when the latter is tilted toward the inverted position shown in Fig. 8.

10 Forcibly fitted within the cylindrical portion of housing 13 is a cage member 22 molded from thin sheet metal and within which are loosely confined a metallic spherical weight 23 and a thin sheet metal disk valve 24, the latter being normally held seated upon the inner marginal portion of flange 17 by said sphere or ball 23 as shown in Fig. 2.

The lower portion of the cage 22 is made cylindrical and of smaller outside diameter than the

20 interior of the housing 13 said cylindrical portion being formed adjacent to its lower end with a circular series of ports 25 (Fig. 6), while the upper end of the cage is closed by an imperforate vaulted top wall 26 whose interior provides a pocket to receive the ball 23 when the bottle is inverted or tilted into pouring position.

When the bottle is inverted or tilted for pouring the contents thereof is free to discharge by gravity through ports 18 and 25 into the annular passageway between housing 13 and cage 22 and thence through port 20 of nipple 21 into the delivery end portion of conduit 14.

25 The cage 22 is made at its lower end with a radial base flange 27 (Figs. 6 and 7) that is formed with a peripheral upstanding cylindrical rim 28 adapted to be forcibly fitted within housing 13 so that the cage is fixedly and immovably held in position within the latter.

The housing 13 is produced from an originally 30 cylindrical sheet metal blank 13a (Figs. 4 and 5) into which the cage 22 containing the ball weight 23 and valve 24 is forced after which the upper portion of the blank is molded, by means of dies, spinning, or otherwise, to form the vaulted roof portion 19 and nipple 21.

35 The above described check-valve unit is of simple, inexpensive and efficient construction, requires few parts and may be cemented or otherwise secured in position within the outlet port or conduit of a bottle or other container to render the same non-refillable.

It will be observed that the vaulted shape of the top portion of the housing serves jointly with the wall of conduit 14 to provide an annular recess or pocket for the cement 16 by which the

unit is fixed in position within said conduit and by which the joint surrounding the unit is sealed.

An advantage to the above described construction is that the cage 22 is disposed directly between and in axial alinement with the ports 18 and 20 of the housing member 13 and therefore the valve 24 and ball 23 are completely isolated and wholly inaccessible so that they cannot be reached and manipulated by means of an instrument inserted in the neck 11 of the bottle.

What I claim is:

As a new article of manufacture, a self-contained check-valve unit of the character described adapted to be fixed within the neck of a bottle to control the flow therethrough, said unit comprising a sheet metal housing element molded to shape from a single piece of sheet metal so as to provide the same with a cylindrical lower portion provided at its top with a vaulted top wall having a centrally disposed constricted outlet port surrounded by a cylindrical external spout flange and having at its lower end an inwardly extending radial valve seat flange surrounding a centrally disposed inlet port; an inverted cage member within said housing element molded to shape from a single piece of sheet metal so as to provide the same with a lower

cylindrical portion having at its lower end an outwardly projecting base flange seated upon said first-mentioned flange of said housing element and forcibly fitted telescopically within said housing element so that it is permanently fixed in position between said two ports, said cage member having an imperforate vaulted top wall serving as a barrier between said two ports and also having its lower cylindrical portion made adjacent to its lower end with a series of laterally directed ports providing communication between the interior of said cage member and a passage existing between the exterior of the latter and the interior of said housing element; a sheet metal disk valve member loosely confined within the cylindrical portion of said cage member and normally seated upon the inwardly extending radial flange of said housing element to close the inlet port of the latter, and a valve-closing ball weight movably confined within said cage member and normally seated directly upon said valve to hold the same in its closed position, said ball weight and valve being both movable into positions below said laterally directed ports when the unit is inverted.

NICHOLAS ARCHIDIACANO.
